PUMP

Clarence E. Fraser and Edward C. Hulsmann,
Chicago, Ill.

Application January 11, 1939, Serial No. 250,279

1 Claim. (Cl. 230—186)

This invention relates to pumps and particularly to pumps for vacuum and compression purposes.

One object of the present invention is to provide a high speed pump operating at high efficiency.

Another object of the invention is to provide a novel means whereby a rotary oscillating motion is created to operate the pistons.

A further object of the invention is to provide means to compensate for lost motion due to friction.

One embodiment of the present invention is shown for illustrative purposes in the accompanying drawings, in which:

Fig. 1 is a sectional elevational view of the pump and illustrating the application of the present invention thereto;

Fig. 2 is a front elevational view of a cylinder head plate as illustrated in Fig. 1 by the lines 2—2;

Fig. 3 is a longitudinal elevational view of the driving mechanism illustrated in Fig. 1 as illustrated by the lines 3—3;

Fig. 4 is a sectional elevation view of a portion of a cylinder head plate, cylinder, piston and push rod and illustrating a detail of the valves and stuffing box guides and a ball cap to receive shims.

In the drawings, the pump is illustrated as a whole (Fig. 1) having cylinders, two in the present instance indicated by the numerals 5—6 with cooling fins 7, mounted circumferentially between two cylinder head plates 8—9.

Pistons, two in the present instance, are positioned in the cylinders 5—6 between head plates 8—9 and indicated by the numerals 10—11. The pistons are provided with push rods substantially continuous and in a manner whereby a push rod 12 is mounted on one end of piston 10 to extend through head plate 8. A stuffing box 21 of the ordinary type is mounted on head plate 8 to provide a guide for push rod 12 (Fig. 1). In like manner a push rod 13 is positioned on the opposite end of piston 10 in a manner to extend through head plate 9 and stuffing box guide 24 on head plate 9.

Piston 11 in cylinder 6 is equipped with push rods 14—15 identical to rods 12—13, and related respectively to stuffing box guides 25—26 mounted respectively, on head plates 9—8 (Fig. 1) and illustrated in detail in Fig. 4.

A drive shaft 23 (Figs. 1 and 3) is positioned through the cylinder head plates 8—9 in bearings 47—48 respectively. Circular parallel discs,

two in the present instance and indicated as 20—21 are mounted outside of the head plates 8—9 on the drive shaft 23 at an angle, in the present instance of thirty degrees.

Mounted on the outer end portions of push rods 12—13—14—15 are ball shaped caps 16—17—18—19 (Fig. 1) to provide contact with the circular angle discs 20—21 and in Fig. 4 illustrates a method to provide for shims 52 contained in the recess 58 of ball cap 18 and bear against the flat surface 51 of push rod 14 mounted on piston 10 in cylinder 5.

The stuffing box guide 25 (Fig. 4) contains packing 55 related to a follower plate 56 and positioned by a lock nut 57.

Valves of the ordinary type and indicated as a whole by the numerals 35—36—37—38 are positioned in head plate 8 (Fig. 1) whereby 36—37 are outlet valves and 35—38 are inlet valves.

Similarly, the valves 39—40—41—42 are positioned in head plate 9 where 40—41 are outlet valves and 39—42 are inlet valves. Manifolds 28—29 are positioned respectively on the head plates 8—9 and related to the outlet valves.

Manifolds 31—34 are related respectively to the inlet valves 38 and 35 on head plate 8 and manifolds 32 and 33 are related respectively to 42 and 39 on head plate 9.

A housing 43 to contain oil or the like is mounted on head plate 8 with a screw type plug 49 and a housing 44 is mounted on head plate 9 to contain oil or the like and provided with a screw type plug 50. The inlet manifolds 31—34 pass through the oil housing 43 (Fig. 1) and the inlet manifolds 32 and 33 pass through the oil housing 44.

The outlet manifolds 28 and 29 (Fig. 2) are provided with a duct 30 on manifold 28 and indicated by the dotted circles (Fig. 1) as the numeral 30 and 30a respectively on manifolds 28 and 29 whereby the outlet valves are related to their respective manifolds outside of the oil housings 43 and 44.

The operation of the pump is substantially as follows:

As suitable rotary power is applied to the drive shaft 23 (Figs. 1 and 3) the circular parallel discs 20 and 21 will rotate, due to their being mounted angularly, in a manner whereby an oscillating motion is created and indicated by the dotted line 4—4. This motion will cause the discs 20—21 to bear against the ball caps 16—19 and 17—18 respectively and cause the push rods 12—15 and 13—14 to reciprocate or move foreward and rearward. As the pushrods are mount-

ed in stuffing box guides, 24—25—26—27 the pistons 10—11 will float in the respective cylinders 5 and 6. The rotary oscillating motion of the angle discs 20 and 21 will create a splash lubrication.

Housing 43 can be provided with a stuffing box for drive shaft 23 and indicated as a whole by the numeral 45. Housing 44 can be provided with a bearing 46 in the present instance as a portion of the housing casting 44 to support the 10 end portion 59 of drive shaft 23 (Fig. 1).

This invention is not confined to a pump as illustrated in the drawings and described in detail but can be applied in various combinations as pointed out in the appended claim.

Having described our invention, what we claim as new and desire to secure by Letters Patent is:

In a pump of the kind described, the combination of a housing, a driving shaft journaled in said housing, said housing having a pair of end 20

chambers adjacent opposite ends of said shaft, said housing having a plurality of bores intermediate said chambers but separated therefrom and extending parallel to said shaft, pistons slidably carried in said bores, compression rods extending from opposite ends of said pistons into the respective chambers, a pair of discs rigidly carried by said driving shaft in said chambers and engageable with the ends of said rods, said discs being disposed in parallel planes non-perpendicular to the axis of said shaft, an inlet and an outlet port at each end of the respective bores, conduits extending from said housing and communicating with respective ports, valves normally closing said ports, said inlet valves biased to open under vacuum and said outlet valves to open under pressure, said end chambers adapted to hold a quantity of lubricating fluid.
